(57) **CLAIM**

The ornamental design for a radio receiver housing for a hidden fence dog containment system, as shown.

DESCRIPTION

FIG. 1 is a pictorial view of the radio receiver housing for a hidden fence dog containment system according to the invention;

FIG. 2 is a front elevation view of the radio receiver housing for a hidden fence dog containment system;

FIG. 3 is a rear elevation view of the radio receiver housing for a hidden fence dog containment system;

FIG. 4 is a left side elevation view of the radio receiver housing for a hidden fence dog containment system;

FIG. 5 is a right side elevation view of the radio receiver housing for a hidden fence dog containment system;

FIG. 6 is a top view of the radio receiver housing for a hidden fence dog containment system; and,

FIG. 7 is a bottom view of the radio receiver housing for a hidden fence dog containment system.
